LIGHT EMITTING GAS DISCHARGE MATRIX DISPLAY PANEL

Gerald E. Wojcik, 4619 282nd St., Toledo, Ohio 43611

Filed Aug. 7, 1970, Ser. No. 24,379

Term of patent 14 years

Int. Cl. D14—01

U.S. Cl. D26—5

FIG. 1

FIG. 2

FIG. 3

FIG. 1 is a front elevational view of a light emitting gas discharge matrix display panel embodying my new design, the rear being identical to the front shown turned 90 degrees with the gas fill tubulation facing away from the viewer;

FIG. 2 is a top plan view thereof, the bottom being a mirror image of the top shown; and

FIG. 3 is an elevational view taken from one side thereof, the opposite side being a mirror image of the side shown.

I claim:

The ornamental design for a light emitting gas discharge matrix display panel, as shown and described.
